UNITED STATES PATENT OFFICE

171,212

HOUSE TRAILER

Solomon J. Kropf, Goshen, Ind.

Application July 28, 1953, Serial No. 26,169

Term of patent 14 years

(Cl. D14—3)

To all whom it may concern:

Be it known that I, Solomon J. Kropf, a citizen of the United States, residing at Goshen, Indiana, have invented a new, original, and ornamental Design for a House Trailer, of which the following is a specification, reference being had to the accompanying drawings, forming a part hereof.

In the drawings:

Fig. 1 is a front perspective view of a house trailer, showing my new design;

Fig. 2 is an enlarged fragmentary rear perspective view; and

Fig. 3 is an enlarged fragmentary front perspective view.

The side opposite the one disclosed in Fig. 1 is substantially the same as the one shown.

The dominant features of my design reside in the portion shown by means of full lines.

I claim:

The ornamental design for a house trailer, as shown and described.

SOLOMON J. KROPF.
